Attorney.

UNITED STATES PATENT OFFICE.

JOHN M. SCHENK, OF WATERLOO, IOWA; ELLA M. SCHENK, ADMINISTRATRIX OF SAID JOHN M. SCHENK, DECEASED, ASSIGNOR TO ELLA M. SCHENK, OF WATERLOO, IOWA.

CONCRETE BURIAL-VAULT.

1,369,985.

Specification of Letters Patent.

Patented Mar. 1, 1921.

Application filed January 22, 1920. Serial No. 353,249.

To all whom it may concern:

Be it known that I, JOHN M. SCHENK, a citizen of the United States of America, and a resident of Waterloo, Blackhawk county,

5 Iowa, have invented certain new and useful Improvements in Concrete Burial-Vaults, of which the following is a specification.

My invention relates to improvements in concrete burial vaults, and the object of my 10 improvement is to provide, in a reinforced concrete vault or casket, having an imperforate body and cover, a joint connection therefor which will permit and insure of hermetically sealing them together.

15 This object I have accomplished by the means which are hereinafter described and claimed, and which are illustrated in the accompanying drawings, in which Figure 1 is a perspective view of a casket of the class 20 described, one end being shown in cross-section, and Fig. 2 is an enlarged detail view showing my improved joint-connection between the upper part of the casket and the depending part of the cover.

25 Similar numerals of reference denote corresponding parts throughout the several views.

The hollow imperforate body 1 of the casket or vault, is open at the top, and is 30 formed of concrete molded about a reticulated reinforcement 2 of the same shape. Surrounding said body and below its upper edge, an integral rib extends from its outside wall at 3, with its outer part extended 35 upwardly, thus providing an upwardly opening groove or trough in said rib around the body 1.

The upper edge part 5 of said body 1 40 preferably has its outer face sloped, and extends suitably above the upper edge of the rib 3. The imperforate cover 6 is also made of concrete molded upon a shaped reticulated reinforcement 7, the cover being somewhat arched in form and having depending edge-parts 8 also outwardly sloped at a slight angle from the vertical so as to inclose in parallel, the raised outer part 5 while depending into the trough 4 in said rib 3, when the cover is in place.

50 The trough 4 is of considerably greater

horizontal width than the depending part 8 of the cover, permitting the reception of the requisite amount of cement or hermetically sealing material 9.

When the joint connection of the casket is 55 thus hermetically sealed, as shown in said Fig. 2, and the casket buried in the ground in a substantially horizontal position, ground water cannot percolate into the casket by seepage through the cementing material 9 60 or any fortuitous cracks or gaps therein. This is due to the provision of the ledge 5 elevated above the rib 3.

If the upper edge of the ledge 5 were at the same level as the upper edge of the 65 raised part of the rib 3, accidental cracks in the cement 9 would permit moisture to percolate into the casket about said ledge 5. The narrow interspace 10 between the opposed parallel surfaces of the ledge 5 and 70 the cover part 8 above the cement 9 is nevertheless wide enough to prevent movement of moisture upwardly therethrough by capillary attraction, while said ledge 5 prevents a transfer of moisture from said interspace thereover, due to the pressure of 75 air under superincumbent cover.

Because of the considerable elevation of the ledge 5 above the trough-bottom 4, the depending part 8 of said cover 6 cannot 80 easily become displaced, even when the casket may not be perfectly level, or in case of its endwise subsidence. This will keep the relation of the parts the same as above described so that the joint therebetween will 85 nevertheless fail to transmit moisture into the casket.

Having described my invention, what I 90 claim as new, and desire to secure by Letters Patent, is:

In combination, an open top imperforate hollow concrete container, a hollow open bottom imperforate cover for said container, with outwardly sloping depending rim, said container having a circumferential 95 ledge positioned below its rim, the ledge being upwardly troughed with its outer rim positioned below the level of the rim of the container, the outer wall of the rim of the container being outwardly sloped, the rim 100

of the cover being seated in the trough of the ledge, spaced therefrom, and impervious sealing-means in said trough embedding the rim of the cover therein only to the level of 5 the upper edge of the rim of the ledge, with the interspace of the cover rim and the container rim unfilled above said sealing-

means and being both relatively long and wide enough to prevent seepage of fluid therethrough by capillary attraction.

Signed at Waterloo, Iowa, this 26th day of December, 1919. ¹⁰

JOHN M. SCHENK.
